THE NORRIS PETERS CO., PHOTO-LITHO., WASHINGTON, D. C.

UNITED STATES PATENT OFFICE.

PATRICK J. COLLINS, OF PHILADELPHIA, PENNSYLVANIA, ASSIGNOR OF ONE-HALF TO
JOSEPH V. HORN, OF PHILADELPHIA, PENNSYLVANIA.

MACHINE FOR SLICING BREAD, CAKE, MEAT, VEGETABLES, &c.

1,203,185.

Specification of Letters Patent. Patented Oct. 31, 1916.

Application filed May 24, 1916. Serial No. 99,504.

To all whom it may concern:

Be it known that I, PATRICK J. COLLINS, a citizen of the United States, residing in the city and county of Philadelphia, State 5 of Pennsylvania, have invented a new and useful Machine for Slicing Bread, Cake, Meat, Vegetables, &c., of which the following is a specification.

My invention consists of a device for slicing or cutting an article of food, such as bread, cake, meat, vegetables, etc., to which, however, the invention is not limited, the members of the device uniformly admitting a knife or blade to be directed step by step 10 to the food, rendering such motion uniform and providing a clean cut for the same, adapting the article of food to be held firmly in place while the knife is being advanced and operated, adapting the article after slicing or cutting to be removed from the device in a convenient manner, means for holding the knife from the article when not required for use, means for guiding the knife in its vertical motions especially when 15 cutting through the article, and other details are presented as will be hereinafter set forth.

The invention is satisfactorily illustrated in the accompanying drawing, but the important instrumentalities thereof may be varied, as long as they are included in the scope of the claims.

Figure 1 represents a side elevation of a slicing machine embodying my invention. 35 Fig. 2 represents a top or plan view thereof. Fig. 3 represents a plan end view and a partial vertical section thereof. Fig. 4 represents a rear elevation, in the present case taken on the left hand end of Fig. 1. Fig. 5 represents a horizontal section of a portion thereof. Fig. 6 represents a longitudinal section of the device. Fig. 7 represents a side elevation of a detached portion on an enlarged scale. Fig. 8 represents a vertical section of a portion on line 8—8 Fig. 7. Fig. 9 represents a perspective view of a pawl employed, and a controlling mechanism of the same. Fig. 10 represents a side elevation of a latch employed. Fig. 11 represents a side elevation of members of the device shown in Fig. 8. Fig. 12 represents a section of a detached portion on line 12—12 Fig. 3. Fig. 13 represents a partial bottom plan and partial

horizontal section of a detached portion. 55 Fig. 14 represents a view of a portion of Fig. 6 showing the knife in lowered position.

Similar numerals of reference indicate corresponding parts in the figures. 60

Referring to the drawings:—1 designates the base of the device, and 2 designates standards which rise movably from the sides of said base and support the auxiliary standards 3, the latter and said standards 2 being separated in vertical direction forming the vertical passages or runways 4 for the blade of the knife 5, it being noticed that the standards 3 are somewhat resilient whereby they may be separated so as to permit of 70 the introduction and removal of the knife. In order to close said standards 3 and preserve the spaced distances of said passages 4 there is pivotally connected with the cross bar 6 which joins a pair of standards 3 at 75 the top thereof, the latch 7 which is adapted to engage the screw stud 8 on the cross bar 9, which latter joins the other pair of the standards 3 at the top thereof, thus retaining said cross bars apart their proper distances forming a space as a continuity of the passages 4, but when the latch is disconnected from said stud 8, said cross bars may be separated allowing the knife to be placed in the passages 4 for slicing purposes 95 or removed therefrom when not required for service.

As has been stated, there are guide passages of different widths for the back of the frame of the knife, and for the blade respectively, hence the latter is moved true in cutting and there is a stop 68 which limits the descent of said back and so prevents the blade cutting into the board and roughening the latter, while the blade cuts through the 95 bread, etc., to full extent to the very surface of the board, but scarcely into said surface. The stop 68 is formed by horizontal shoulders or ledges at the base of the walls of the passages 4 of the upper standards 3, it being evident that on the descent of the knife the back of the knife-frame 14 abuts said shoulders and so stops the cutting edge of the blade of the knife exactly at the proper place at the bottom of the slice of bread, 100 etc., and the surface of the board without cutting into the latter.

In order to support the knife in elevated

position prior to use, I employ the hanger 10 which is somewhat of hook form and connected with the rock shaft 11 mounted on the standards 3, see Figs. 3 and 6, it having a handle 12 which projects rearwardly therefrom and has connected with it the spring 13 which is also connected with the adjacent standard 3, it being noticed that when the hanger is moved rearwardly by 10 the handle 12, the knife may be placed in the passages 4 and when the hanger is let-go owing to the spring 13, it returns to its normal position when the back of the knife carrying frame 14 may be hung on said hanger in elevated position preparatory to use.

To permit the hanger to move to and fro and cross the passages 4 in either direction, the standards 3 have therein the slots 15 and 16, see Fig. 6. When the knife is to be released, it is slightly raised from the position shown in Fig. 3, and the hanger is drawn back whereby the knife is free to be lowered to slice or cut the bread, cake, or 25 other food or article below the blade thereof, said food or article being rested on the food supporting board 17.

It will be noticed that the passages 4 in the upper standard 3 are wider than those 30 in the lower standard 2, so that the back of the knife-carrying frame 14 will move in the former passages, said back being thicker than the blade of the knife 5 which is thin in its nature, the latter being movable vertically in the passages of both standards, hence both the blade and the back frame thereof are guided in their motions and the blade is steadied and adapted to move true especially while slicing or cutting the food, 40 the blade then occupying the narrow passages of the lower standards 2.

The board or bed 17 is the support of the food while being cut, it being made preferably of wood, so that when the knife blade 45 descends to full extent it may contact therewith and so not be injured, said bed being stationarily mounted on the base 1 of the device.

On the under side of the bed is the longitudinally extending rack 18 with which 50 meshes the pinion 19, whose shaft is mounted on the longitudinally movable traveler 20, the latter consisting of a plate or bar 21, whose upper portion is guided on ways 22 on the underside of the base 1, it being noticed that the standards 2 rise from boxes 23 on the ends of said plate, the inner sides of said boxes being guided on ways 24 on the outer sides of the base 1.

55 25 is a pinion on a shaft parallel with the countershaft 27 of the pinion 19, and this pinion 25 gears with a pinion 26 on said shaft 27 which latter is mounted on the plate of the traveler 20, and has on one end the ratchet 28 whose teeth are adapted to be

engaged by the pawl 29 pivotally mounted on the lever 30 which is freely mounted on the shaft of the pinion 28.

The lever 30 is deflected at the top forming the hand or finger-engaging member 31* 70 for conveniently operating said lever and consequently the pawl, ratchet and pinions, whereby as the pinion 19 rotates and it engages the rack 18 and rides thereon, the traveler and connected parts are advanced 75 step by step, placing the knife successively over a fresh place of the food to be cut or sliced. When said knife is lowered it cuts through the food and so slices it in pieces, one after the other.

In one of the side boxes 23 adjacent to the lever 30 is the plate 31 in which are openings 32 arranged in circular order and adapted to register with similarly disposed openings 33 in said box 23.

80 34 designates a pin which is adapted to be passed through either of the openings 33 or 32 that are in register, so as to be in the path of the lever 30, see Fig. 11, whereby the throw of said lever may be regulated so as 90 to advance the traveler 20 to such extent and with it the knife so as to cut the food in thicker or thinner slices. The article in the present case is a loaf of bread as shown in dotted lines.

95 The pawl 29 is held in contact with the tooth to which it is advanced by the action of the lever 30 by the spring 35 which is secured to the lever and bears against the back of the pawl, as most plainly shown in Fig. 7. Bearing against the heel of said pawl is the dog 36 which is connected pivotally with the box 23 as at 37, said dog having in it the obliquely extending slot 38 which receives the pin or stud 39 on the 105 slideable bar 40 which is guided in ways on the box 23. Connected with the pawl 29 by the stud 41 there is the spring 42 which is connected also with said box 23 as at 43. In the box 23 is the spring pressed pin or 110 plunger 44 which is passed through the segmental slot 45 in the side wall of said box and provided on its inner end with the head 46 which at a certain time is adapted to rest against the side face of the pawl 29, 115 and at another time is adapted to spring into the recess 47 in said face, see Figs. 8 and 9, it being noticed that when the food has been sliced to full extent the bar 40 is moved in the present case to the right, whereby the 120 stud 39 in the oblique slot 38 of the dog 36 draws down said dog and forces its nose against the heel of the pawl, thus raising the tooth or point portion of the latter free of the ratchet 28. Then the recess 47 in the 125 pawl is placed in the path of the head 46 of the pin 44 when said head springs into said recess and so holds the pawl in inoperative position, whereby the traveler and connected parts, including the standards 2 and 130

3 may be run back to normal position, in the present case, the right end of the device.

The motions of the traveler in opposite directions are limited by the stop members 5 48 on the terminal members of the ways 22 on the base 1. Adjustably secured to the finger piece 31* of the lever 30 is the rod 49 which rises therefrom and has on its upper end the head 50 which when said lever is 10 pressed down to advance the pawl 29 is adapted to contact with the top of the article of food which in the case of a loaf of bread being irregular in its formation is pressed down on the board 17 and so steadied 15 thereon preparatory to the sliding operation as will be most plainly shown in Fig. 1.

On the opposite ends of the board 17 are the upright plates 51, 52, between which the article of food, say the loaf of bread is held 20 in a firm manner, the plate 52 being pivotally connected with said board as at 53, whereby said plate may be turned in the direction of the arrow, Fig. 1, to permit the ready application of the loaf of bread upon 25 the board, and the subsequent removal of the same when sliced.

On the rear of the plate 52 is the vertically movable bar 54 having at the top the downwardly extending teeth 55 which are 30 adapted to engage the terminal portion of the loaf of bread, and hold down the same, said bar being controlled by the screw 56 which is secured to the plate 53 and passes through the vertically-extending slot 57 in 35 said bar 54. On the outer end of said screw is the thumb nut 58 which is adapted to tighten against said bar and hold it in vertically adjusted position. When the nut is unscrewed, the bar is adapted to rise by the 40 action of the sprngs 59 which are connected with said bar and the side members of the plate 52, in which case the teeth 55 rise with said bar 54, and so releases the top of the loaf of bread of the holding action of said 45 toothed bar 55.

On a side member of the plate 52 is fitted and guided the spring actuated slide 60 which in normal position extends forwardly from said plate so as to overlap the side of 50 the terminal portion of the loaf of bread, and serves to retain said portion true in position during the slicing operation. When the latter is accomplished, said slide may be pushed outwardly, in the present case, 55 to the left, and so be removed from the terminal portion of the loaf of bread, assisting to permit the removal of the sliced loaf laterally from the board 17.

In order to hold the pivotal or swinging 60 plate 52 in fixed upright position there is mounted on the same the latch 61 which is adapted to engage the post 62 which rises from the board 17, as plainly shown more particularly in Figs. 4 and 6.

65 On one of the standards 3 is the verti-

cally-arranged roller 63, whose bearings are on the swinging frame 64, the latter being pivotally mounted on the ears 65 on the sides of the standards 3, and engaged by the springs 66 so that said roller 63 is pressed and held inwardly, as shown in Figs. 2 and 3, so as to be normally in the path of the side of the loaf of bread, but when the latter is to be placed in the position on the board 17, said roller is moved into the recess or slot 67 in the standard 3, so the loaf of bread may be properly placed on the board 17 between the opposite standards 3, preparatory to slicing, and then said roller presses against said side of the loaf of bread as the standards are advanced by the carriage, said roller then riding on said side of the loaf and holding the loaf pressed against the opposite standard and so steadied while being sliced.

It is evident that when the loaf of bread is properly placed on the board and retained in position in the manner and by the means stated, the knife is lowered and cut through the loaf forming the first slice thereof. Then the knife is raised, and the lever operated when the knife is carried a distance to make the next slice. The knife is lowered and so cuts through a fresh place of the loaf, making the second slice thereof, and so the operations are continued throughout the loaf or as long as desired. When the slicing is ended, the bar 46 is moved, in the present case, to the right, whereby the pawl 29 is raised as has been stated, and the ratchet 28 released therefrom, and so the carriage may be run back to its first position. The bar 54 is released whereby its teeth 55 rise from the loaf of bread, after which the latch 61 may be removed from the post 62, and the plate 53 swung outwardly and the slide 60 pushed back, so that the sliced loaf of bread may be conveniently removed from the board 17, it being noticed that the slices are uniform and clean cut from top to bottom.

Having thus described my invention what I claim as new and desire to secure by Letters Patent, is:—

1. In a slicing machine, a stationary base, a traveler mounted thereon, means for guiding a knife to said base, means for sustaining the frame of the knife to hold the latter inoperative and means for operating said sustaining means to remove it from said frame and permit the knife to be operative.

2. In a slicing machine, a stationary base, a traveler mounted thereon, means on said traveler having vertical passages of different widths for guiding a vertically movable knife to said base through the articles to be sliced, and a knife having a back thicker than its blade and occupying the wider passages.

3. In a slicing machine, a stationary base,

- a traveler mounted thereon, means on said traveler having vertical passages of different widths for guiding a vertically movable knife to said base through the articles to be sliced, a knife having a back thicker than its blade and occupying the wider passages.
4. In a slicing machine, a base, a traveler, standards thereon having therein vertical passages for guiding a knife to said base, a hanger on said standards adapted to sustain the frame of said knife and hold the latter inoperative, and means for operating said hanger to remove it from said frame and permit the knife to be operative.
5. In a slicing machine, a base, a traveler mounted thereon, gearing on said base and traveler, shafts for said gearing, a ratchet on one of the shafts of said gearing, a lever mounted freely on said shaft, a pawl on said lever adapted to engage said ratchet, means for retaining said pawl in engagement with said ratchet, and means for throwing off said pawl from said ratchet.
6. In a slicing machine, a base, a traveler mounted thereon, a lever on said traveler, gearing intermediate the latter and said lever, and a pawl and ratchet mechanism adapted to impart intermittent motion to said traveler, a dog on said traveler adapted to engage the heel of said pawl, a slicing member on the traveler, and means on said member and dog whereby said dog is adapted to disengage said pawl from said ratchet.
7. In a slicing machine, a base, a traveler mounted thereon, a lever on said traveler, pawl and ratchet mechanism, gearing intermediate of the ratchet and said base, and a plunger on said traveler, said pawl having therein a recess into which the head of said plunger may be sprung to render said pawl operative on said ratchet and from which it may be removed to remove said pawl from said ratchet and render the former inoperative to permit the return motion of the traveler.
8. In a slicing machine, a base, a traveler mounted thereon, a lever on said traveler, pawl and ratchet mechanism, gearing intermediate of the ratchet and said base and said traveler having in its side spaced-apart openings, and a pin adapted to be placed in either of said openings in the path of said lever to limit the throw of the latter and consequently the degree of the intermittent motions of the traveler.
9. In a slicing machine, a base, a traveler mounted thereon, a knife guiding standard on said traveler, and a pressure device on the inner side of said standard adapted to 60 bear against the article to be sliced and placed on said base during the motion of said traveler, said device being composed of a roller-like member and spring engaged bearings for the axis of said member.
10. In a slicing machine, a base, a knife-carrying traveler mounted thereon, a lever on said traveler, gearing intermediate said base and lever whereby intermittent motion is imparted to said traveler and means on 70 said lever extended transversely over said base for contact with the upper face of the article being sliced and adapted to exert downward pressure on the same.
11. In a slicing machine, a base on which 75 an article to be sliced may be placed, means for guiding a knife to said base, means for sustaining the frame of the knife to hold it inoperative, means for operating said means to permit the knife to be operated, 80 and a stop plate at the end of said base where the slicing ceases.
12. In a slicing machine, a base on which an article to be sliced may be placed, means for guiding a knife to said base, means for 85 sustaining the frame of the knife to hold it inoperative, means for operating said means to permit the knife to be operated, a stop plate at the end of said base where the slicing ceases, and means on the side of 90 said plate to engage the side of the adjacent portion of said article.
13. In a slicing machine, a base on which an article to be sliced may be placed, a stop plate on the end of said base where the slicing of said article ceases, and a longitudinally acting slide on the side of said plate adapted to overlap the side of the adjacent portion of said article.
14. In a slicing machine, a stationary base, 100 a traveler mounted thereon, means for advancing said traveler and means arranged to press against the side of a loaf of bread and to steady the same while being sliced, said pressing means embodying a roller-like 105 member and spring-engaged bearings for the axis thereof, the standard of said traveler having a slot through which said roller-like member is movable.
